TOOL CHEST OR SIMILAR ARTICLE

Manfred Karl Hegemann, Nyack, N.Y., assignor to Liberty Steel Chest Corporation, Rochester, N.Y., a corporation of New York

Filed Nov. 6, 1963, Ser. No. 77,311

Term of patent 14 years

(Cl. D87—5)

FIG. 1

FIG. 2

FIG. 3

FIG. 4

FIG. 5

FIG. 6

FIG. 1 is a top plan view of a tool chest or similar article, showing my new design;

FIG. 2 is a front elevational view thereof;

FIG. 3 is a rear elevational view thereof;

FIG. 4 is an end elevational view thereof;

FIG. 5 is a fragmentary section illustrating the grooved formation of part of the top and part of the front of the chest; and

FIG. 6 is a fragmentary vertical section taken transversely through the upper part of the chest near the left end thereof.

I claim:

The ornamental design for a tool chest or similar article, substantially as shown and described.
